DENISON BABCOCK, OF NEW YORK, N. Y., ASSIGNOR TO NATHAN J. LEIGH, OF NEW YORK, N. Y.

DISPLAY DEVICE

Application filed March 5, 1929. Serial No. 344,536.

This invention relates to display devices.

The general object of this invention is the provision of a simple and efficient display device for displaying articles and advertising matter relating to the article displayed.

A further object of the invention is the provision of a display device including means for displaying articles and advertising matter relating to the articles which is so constructed that the advertising matter may be changed by removing the standard carrying the advertising matter and substituting a new standard carrying advertising matter therefor.

These objects are accomplished by providing a base, a display card having a standard attached thereto, said standard being adapted for mounting on the base and for supporting a shelf behind the display card.

These and other objects of the invention will be more clearly understood from the following detailed description and accompanying drawings.

Figure 1 is a perspective view of the display device.

Fig. 2 is a front elevation of the display device.

Fig. 3 is a vertical section along the line 3—3, Fig. 2.

Fig. 4 is a horizontal section along the line 4—4, Fig. 2.

Fig. 5 is a perspective view of the display card, showing the collapsible standard.

Referring to the above mentioned drawings, the invention includes a base 10. Mounted on this base 10 is a block 11. A display card 12 has a collapsible standard 13 attached thereto. As will be observed in Fig. 1, the lower end of the display card is

in line with the lower end of the collapsible standard while the upper end of the display card extends above the upper end of the collapsible standard. A shelf 14 having a block 15 attached to its lower face is mounted on the standard 13. In this particular case, the

standard 13 is hollow and so shaped that it will fit over the block 11 and receive the block 15 attached to the shelf 14. Thus when the standard 13 is seated on the base 10 it fits over the block 11 which serves to retain the standard in position on the base. The block 15 attached to the shelf projects into the standard 13 and serves to retain the shelf 14 in position.

In using this device, the advertising matter is mounted on the display card 12, and the article to be displayed and to which the advertising matter refers is supported on the shelf 14. When it is desired to display articles different from those referred to in the advertising matter a new display card to which a collapsible standard 13 is attached is substituted for the one originally used.

I would state in conclusion that while the illustrated example constitutes a practical embodiment of my invention, I do not limit myself to the exact details herein illustrated since manifestly the same can be considerably varied without departing from the spirit of the invention as defined in the appended claims.

I claim:

1. A knock-down display device comprising a rigid and solid base with a boss on its upper surface; a rigid and solid shelf element having a plane upper surface adapted to receive articles to be displayed, and a boss on its under-surface; and a tubular cardboard column member having a polygonal cross-section to permit collapsing thereof into a substantially flat condition; said bosses conforming to said cross-section so as to telescope removably and frictionally within opposite ends of said column member.

2. A knock-down display device comprising a rigid and solid base with a rectangular boss on its upper surface; a rigid and solid shelf element having a plane upper surface adapted to receive articles to be displayed, and a rectangular boss on its under-surface;

and a tubular cardboard column member having a rectangular cross-section conforming to said bosses; whereby said column member may be collapsed into a substantially flat condition when the device is knocked down, and whereby the ends of said column member may be removably and frictionally telescoped around said bosses respectively when the device is set up.

10. Signed at New York city, in the county of New York and State of New York, this 2nd day of March, A. D. 1929.

DENISON BABCOCK.
